UNITED STATES PATENT OFFICE

LESLIE R. NEED, OF SOUTH BEND, INDIANA, ASSIGNOR TO WESTINGHOUSE ELECTRIC AND MANUFACTURING COMPANY, A CORPORATION OF PENNSYLVANIA

DESIGN FOR A LAMP STANDARD

Application filed January 20, 1930. Serial No. 34,191. Term of patent 14 years.

To all whom it may concern:

Be it known that I, LESLIE R. NEED, a citizen of the United States, residing at South Bend, in the county of St. Joseph and State of Indiana, have invented a new, original and ornamental Design for a Lamp Standard, of which the following is a specification, reference being had to the accompanying drawings, constituting a part hereof.

Figure 1 is an elevational view of a lamp standard showing my new design, and

Fig. 2 is a sectional view of the standard taken along the line II-II of Fig. 1.

The essential feature of my design comprises a post having a gradual curve of large radius adjacent the lower end of the post body in combination with a base comprising a relatively long upper cylindrical portion and a lower short cylindrical portion having a greater diameter than the upper portion.

I claim:

The ornamental design for a lamp standard substantially as shown and described.

In testimony whereof, I have hereunto subscribed my name this 11th day of January, 1930.

LESLIE R. NEED.
